INVENTOR:

Chester Hunt

UNITED STATES PATENT OFFICE.

CHESTER HUNT, OF LYNN, MASSACHUSETTS, ASSIGNOR TO UNITED SHOE MACHINERY CORPORATION, OF PATERSON, NEW JERSEY, A CORPORATION OF NEW JERSEY.

PROCESS OF MAKING HEELS.

Application filed February 14, 1918. Serial No. 217,228.

To all whom it may concern:

Be it known that I, CHESTER HUNT, a citizen of the United States, residing at Lynn, in the county of Essex and State of Massachusetts, have invented certain Improvements in Processes of Making Heels, of which the following description, in connection with the accompanying drawings, is a specification, like reference characters on the drawings indicating like parts in the several figures.

This invention relates to heels and to methods of economical production thereof. In view of the advancing cost of leather, heels are today largely made to comprise base lifts (usually two) of leather to constitute the wear-resisting portion, and body lifts (varying in number from three to ten according to the height of the heel) cut from leather-board and assembled with the base lifts into a heel pile, glued together, and also usually metallic fastened, then pressed for a few hours to hold the lifts in intimate contact while the glue sets, then later compressed, and finally edge trimmed to produce even-edge surfaces. This method is slow and expensive in labor cost and only about 80% of the leather-board stock can be cut into lifts, the remaining 20% being scrap that is good only for fuel or to be worked over again, like shoddy.

The present invention has for its object the more expeditious production of heels, eliminating the waste referred to and very largely reducing both the labor cost and the length of time during which the heel is in process. My method also results in a superior heel, particularly for men's wear and for other uses where a medium height heel is required.

In one of its aspects this invention consists in assembling a base lift or element of sheet material, such as leather, and a relatively thick body lift or element of such material as leather-board stock from which the water has been largely extracted but which is still mellow enough to insert fastenings through without liability of cracking, uniting said lifts by a marginal row of fastenings having clinching formations on one end and holding heads or clinching formations on the other end, and subjecting said lifts to compression and clinching the fastenings to hold said lifts or elements in compressed relation. Advantageously the

base lift may be prepared by inserting therethrough a marginal row of headed and pointed nails and the base lift may or may not be supplemented by a second lift glued or otherwise secured thereto and which covers the nail heads; the body lift or element may be prepared by subjection to moisture extraction and molding pressure to produce a properly shaped, compressible and permeable body element devoid of excessive moisture; and also advantageously a seat lift or a rand may be provided upon the outer face of which to clinch the nails. When properly prepared and assembled, the heel elements are forced together and subjected to compression, a clinching plate being used at the seat end of the heel. The compression not only closes the joints between the several elements and solidifies the body element but also molds said elements, producing a smooth edge face thereon which can be scoured and finished with little or no edge trimming of the heel. The compression forces the nails home and clinches the points, causing the said nails to maintain the several elements under compression.

As I am advised, both the method herein disclosed and the product resulting therefrom are new. I will now describe the same more in detail with the aid of the accompanying drawings and will then point out the invention definitely in the claims.

Fig. 1 of the drawings shows in group relation the several elements or lifts.

Fig. 2 is a view of the assembled and compressed heel.

Fig. 3 shows the compressing, molding and fastening operation.

Fig. 4 is a detail illustration of the effect of compression in reducing the thickness of the heel body element and the effect of the marginal row of nails in maintaining the compression.

Fig. 5 is a view of the heel of this invention attached to a shoe.

As I have practised the method with best results a base lift 2 of suitable leather or of tough substantially uncompressible fibre-board is provided with a marginal row of headed nails 4 as shown in Fig. 1, and a cover lift 5 is secured by glue to the lift 2 over the nail heads. The lifts 2 and 5 are preferably died to exact shape desired in the heel, no edge trimming being contemplated, and if the heel is to have any taper

the lifts are preferably cut with a proper bevel.

A heel body element 10 is prepared as a block of suitable composition, herein referred to for the purpose of designation as leatherboard stock. From such stock the moisture is largely extracted, leaving the molded block 10 responsive to heavy compression and mellow enough to permit driving nails through 10 without liability of cracking the block. The preparation of such blocks may or may not be carried on as a preliminary operation, preceding the date of their incorporation into the heel by a sufficient period to allow 15 the block to acquire the desired degree of toughness while retaining suitable compressibility and permeability.

A seat rand 15 or a seat lift will be prepared of the size predetermined for the seat 20 end of the heel. In the broadest aspect of the invention, neither the rand 15 nor the cover lift 5 are essential and it is also within the invention to omit the preliminary insertion of the headed nail 4 into the lift 2 25 and to drive said nails after the several elements have been assembled and while they are held under partial or complete compression.

The elements are now assembled in the 30 order indicated in Fig. 3 within the molds of the compressor, the machine being of any suitable construction such for example as the compressor shown in United States Letters Patent No. 776,823 granted Dec. 6, 1904, 35 C. L. Allen. The side molds are first closed to effect precision of alignment of the elements and then the elements are pressed vertically together, preferably simultaneously with lateral molding pressure which effects 40 precise shaping of the edge faces of the heel, with rubbing pressure on the body element 10, so that the completed heel is adapted to 45 be scoured and finished without edge trimming. As the elements are pressed together 50 the nails are forced through the permeable element 10, which is subsequently to be condensed and hardened by the compression. The nails used are of such length that, although they may not extend fully through 55 element 10 before pressure is applied, when the elements are reduced in thickness by the well-known power of said machine, the nails will be forced through element 10 and through the rand 15 and clinched or headed 60 down upon the top face of the rand as shown in Figs. 1 and 4. It will be noted that the nails are clinched when the heel elements are under compression and reduced to minimum thickness and that the lifts 2 65 and 15 are relatively tougher than the material of element 10 so that they constitute the equivalent of washers between which the compressed element 10 is held by the headed ends of the marginal row of fasteners which constitute in effect headed rivets.

This produces a strong, light heel, at a minimum labor cost, with no waste of materials, no delays for the setting of glues or pastes, no long maintenance under pressure, a compressed heel fully completed for attachment to its shoe (Fig. 5) being produced in a single operation. This heel may be made particularly well adapted, by reason of the marginal anchorage of its parts together as securely as if they were riveted, 70 for attachment to shoes by inside fastening, as shown, for example, in Fig. 5, and it is especially well adapted to the manufacturer for use with short soles because it can be molded to its final size, requiring no reduction by the usual edge trimming operation. It therefore constitutes a reliable member with which to match the sole end 16 as to width. I have used with good results a wide variety of compositions for the body element 10, including leatherboard stock mixed with Portland cement to influence 75 hardness, fine cork to influence weight, and selected coloring materials to match the uppers of the shoes in which the heels were to 80 be incorporated.

Having explained the nature of this invention and described how the method may be successfully practised and the heel produced, I claim as new and desire to secure by 95 Letters Patent of the United States:

1. That improvement in methods of making heels which consists in providing a top element and an integrally continuous bottom element of sheet material to form 100 the tread and seat lifts of a heel, arranging between said elements a preliminarily shaped body element of homogeneous semi-plastic material equal in thickness to a plurality of heel lifts, and then simultaneously compressing said elements and driving fastenings positioned to attach together 105 said top and bottom elements and said body portion.

2. That improvement in methods of making heels which consists in placing in a mold an element which is to form one of the exposed faces of a heel having therein a marginally arranged row of fastenings extending into the space of the mold, placing in the mold an element to constitute an opposite face of the heel, placing a body element of leatherboard stock between said first-named elements, said last element being capable of substantial compression and of ready perforation by the nails, and then compressing said elements in the mold to cause the nails to perforate the body element and to become clenched in the opposite surface element.

3. That improvement in methods of making heels which consists in providing a nail holding element, inserting nails in upstanding relation marginally thereof, providing a mass of leatherboard pulp to form the 130

body element of the heel, partially extracting the water therefrom to render the mass homogeneous and firm but compressible and capable of perforation by the nails, positioning the said body element over said nail holding element, assembling a seat lift element or rand with said body element, and subjecting said elements to vertical and lateral compression to cause the nails to 10 perforate the body element and become clenched in the seat lift element and the body element to be compressed and held under compression by the nails.

4. That improvement in methods of making heels which consists in providing a toplift having fastenings arranged in upstanding relation about its marginal portion, preparing a homogeneous mass of leatherboard stock of sufficient volume and 20 of a shape to form the body portion of a heel and of the thickness of a plurality of lifts, the mass being of firm consistency but penetrable by fastenings without liability of cracking, superimposing the mass on the 25 fastenings, placing a seat lift on the mass, and subjecting the mass to molding pressure to cause the mass to be compressed between the toplift and the seat lift and the fastenings to penetrate the mass and clench 30 in the seat lift in a single molding operation.

5. That improvement in methods of mak-

ing heels which consists in assembling in superimposed relation a base element of sheet material, a body element of imperforate leatherboard stock from which the moisture has been largely extracted but which is still mellow enough to permit the passage of fastenings through it without liability of cracking, and a seat lift or rand 35 of tough sheet material, then passing holding means through the body portion about its margin, and then subjecting said elements to pressure sufficient to reduce the thickness of the assemblage and simultaneously causing the holding means to be headed to hold the assemblage under compression.

6. That improvement in methods of making heels which consists in providing top 50 and bottom elements to form respectively the tread and seat lifts of a heel, arranging between said elements an integral body element of homogeneous, semi-plastic material equal in thickness to a plurality of heel lifts, 55 and then compressing said elements and while the elements are under compression driving fastenings positioned to attach together said top and bottom elements and said body portion and hold them under 60 compression.

In testimony whereof I have signed my name to this specification.

CHESTER HUNT.
